UNITED STATES PATENT OFFICE.

HARRY A. WARDY, OF KALAMAZOO, MICHIGAN.

FILING-CABINET.

1,146,778.

Specification of Letters Patent.

Patented July 13, 1915.

Application filed March 18, 1914. Serial No. 825,636.

To all whom it may concern:

Be it known that I, HARRY A. WARDY, a citizen of the United States, residing at the city of Kalamazoo and State of Michigan, have invented a new and useful Filing-Cabinet, of which the following is a specification in such full, clear, and precise language as will enable those skilled in the art to understand the same.

10 This invention relates to improvements in filing cabinets.

In my application Serial Number 650,936, filed September 23, 1911, I illustrated, described and claimed certain improvements 15 in filing cabinets whereby folders or cards filed in the cabinet could be mechanically selected and withdrawn in classes; in another application, Serial Number 791,253, filed September 22, 1913, I illustrated, described 20 and claimed an improvement comprising mechanical means for readily and accurately adjusting the device for selecting and withdrawing the folders or cards.

My present invention is a continuation or 25 a carrying forward of the original broad conception, and includes an improved embodiment of mechanism for positioning the selecting device, with various other novel and advantageous features and improvements 30 which will be readily understood by those skilled in the art, from the disclosure hereinafter set forth.

In the drawings in which I have illustrated a preferred embodiment of my improvements aforesaid—Figure 1 is a plan view of the cabinet showing one of the sides thereof in dropped or horizontal position. Fig. 2 is a transverse sectional view of the cabinet in the same adjustment as is illustrated in Fig. 1. Fig. 3 is a side elevation of one of the sides of the cabinet in which my present improvements have been embodied. Fig. 4 is a fragmentary sectional view illustrating the details of construction 45 and the manner of engaging the selecting device with the engaging means carried by the folder or card. Fig. 5 is a horizontal section substantially on the line 5—5 of Fig. 3. Fig. 6 is a horizontal section substantially on the line 6—6 of Fig. 3, and Fig. 7 is a transverse section on the line 7—7 of Fig. 3.

In the embodiment of my invention illustrated in the drawings A indicates a cabinet 55 or case which comprises end walls 1, a bottom wall 2, and side walls 3, each of the

side walls having hinged connection with the bottom wall 2. The side walls are preferably of sheet metal whose lower edges embrace rods 4, whereby the sides are pivotally supported, and upon which the sides may be moved from vertical to horizontal positions. In order to limit the outward and downward movement of the side walls 3 and to support them in horizontal position I provide arcuate supporting links 5 having their outer ends attached to said walls adjacent to each end thereof. The links 5 are arranged to slide in guides 6 secured near the side edges of the front and rear walls. At the angle of the side and bottom walls I preferably secure a longitudinal guide strip 7, which is adapted to maintain the folders or cards placed in the cabinet in longitudinal alinement, so that their outer edges lie in the same vertical planes. It is contemplated that the folders or cards shall be arranged in the cabinet, one behind the other, in any predetermined order, and that said folders or cards be selected and withdrawn in predetermined selected classes, such, for instance, as by date or subject.

In the embodiment of the invention illustrated I have shown folders B provided with a calendarial index at each side thereof, the dates from 1 to 16, inclusive, being paired near one vertical edge and the dates for the remainder of the month being paired near the opposite vertical edge, on the front face of the folder. When the folders are arranged in the case in any predetermined order, such, for instance, as in alphabetical arrangement, and it is desired to withdraw certain of said folders in a predetermined class, the hooks or clips 8 are adjusted upon the side edges of the folders so that the selected index character representing the class in which the folders are to be withdrawn will center in the aperture in the body of the hooks, as clearly appears in Fig. 4 of the drawing. Since all of the folders or cards are provided with uniformly positioned index characters, when the folders are placed in the cabinet all of the index hooks or clips in a given class or series will be in horizontal alinement. All of the horizontally alined hooks of each series are thus in a position to be engaged by the horizontal selecting rod adjusted for such predetermined class in the manner herein described.

Each of the hinged sides of the cabinet

is equipped with a device for selectively engaging the hooks and withdrawing the selected cards or folders; and, since the selecting devices at opposite sides of the cabinet 5 are duplicates, it is necessary only to describe one of them. The rock-shaft or rod 9 is journaled in two bearings 10 which are longitudinally movable on said rod or shaft, and pivotally supported on the upper ends 10 of two levers 11. The lower ends of the levers 11 are adjacently supported upon pivots 12 near the lower edge of the side wall with which said levers coöperate. Thus, by manipulation of the levers 11 the rock-shaft 15 or rod 9 may be raised or lowered, the bearings 10 sliding on the said rod or shaft. The levers 11 are connected to a controlling member 13 by links 14 whose lower ends are pivoted to said levers, respectively, and 20 whose upper ends are pivoted to said member 13. The member 13 is movable vertically, and is guided in a vertical slot 15 in the side wall. Laterally extended portions 16 of the member 13 engage against the outer 25 face of the side wall, and assist in retaining the parts in accurate adjustment. A lever 17 has one end pivoted to the outer side of the wall at 18, and is provided with a longitudinal slot 19 which receives a headed projection 20. The free end of the lever 17 is manually engageable, so that said lever is operative to raise and lower the member 13, and thereby the rock shaft or rod 9. Each 30 end of the shaft or rod 9 supports an arm 21, and said arms are connected to and support a bail-rod 22, so that when said shaft or rod 9 is rocked the bail 22 will be moved. By moving the free end of the lever 17 vertically the member 13 may be moved vertically to any desired position; and, since the member 13 controls the levers 11, said levers 35 11 will be operated by said member 13. The bearings 10 will thus be moved toward each other or away from each other, and the rod 40 or shaft 9 will be lowered or raised by said bearings. The lever 17 is preferably provided with a projection 23 adapted to engage in equally spaced openings or indentations 45 24 in the exterior surface of the side wall 50 of the cabinet in order to hold said lever in any of the adjustments in which it may be placed. Thus, by manipulation of the lever 17 the rod or shaft 9 may be moved vertically to any desired adjustment and may be 55 latched in any of its several adjustments.

An index support 25 is supported by the rod or shaft 9 near each end of the rod or shaft 9. The said index supports are movable with the rod or shaft 9, and are guided 60 in their vertical movements by slots 26 in the side wall of the cabinet, so that when the rod or shaft 9 is moved vertically by manipulation of the lever 17, the index supports are moved therewith. The index supports 65 include flanges 27 engaging against the inner

surface of the side wall, and they also include flanges 28 engaging against the outer surface of the side wall to prevent the index support from turning with the rod or shaft when said rod or shaft is rocked as herein-after described. Pointers 29 are supported by the index supports on the outer side of the cabinet wall and register opposite the date or selecting scales 30 formed or affixed upon the outer surface of the cabinet wall, 70 75 so that it may be definitely known by the operator with which of the hooks 8 the selecting device is positioned to engage. Thus, assuming that the selecting device at one side of the cabinet is positioned to engage with the uppermost hooks 8, the pointer 29 will be positioned opposite the index characters 17-18 at that side of the cabinet as illustrated in Fig. 3. Or the selecting device may be moved downwardly by manipulation of the lever 17 in position to engage with another series of hooks 8, as illustrated in Fig. 5; so that the selecting device may be moved to any position to engage with any series of hooks 8, at the will of the operator. 80 85 90

It is desirable that the bail rod 22 be retained in the same vertical plane with the rock shaft or rod 9, so that said bail may be moved vertically to any desired adjustment without interfering with any of the projecting hooks 8. Preferably the rod 22 is retained below the rod or shaft 9 as illustrated in Fig. 1 and Fig. 2, and such adjustment may be maintained by a spring 31, (Fig. 1), encircling the rod or shaft 9 and having one end connected with the index support 25 and the opposite end connected with one of the arms 21. When the rod or shaft 9 is moved to the desired adjustment it is necessary that the bail rod 22 be moved into engagement with the adjacent series of hooks 8, and for moving the said rod 22 into engagement with the adjacent series of the hooks 8, I provide a key or lever 32. The said key or lever 32 is attached to the rod or shaft 9 and is accessible from the exterior of the side wall, so that by depressing the said key or lever the shaft 9 will be rocked in its bearings and the rod 22 will be engaged with the corresponding series of hooks 8, as illustrated in Fig. 4. Preferably the key or lever 32 is provided with an extension 33, (Fig. 4), engaging with the rod 22, thereby forming a connection between the rod or shaft and the rod 22 intermediate of their ends in order to strengthen and prevent bending of the rod 22 as a result of its frequent use and operation. Thus, the rod or shaft 9 is capable of two movements; one of said movements being vertically by manipulation of the lever 17 as required to position said rod or shaft opposite the selected series of hooks 8; and the other operation is a rocking movement, effected by manipulation of the key or lever 32 in order to 110 115 120 125 130

engage the rod or bail 22 with the selected series of hooks 8. After the engagement of the rod or bail 22 with the hooks 8 has been effected the side of the cabinet may be swung outwardly upon its supporting rod or axis 4 to withdraw selected cards or folders B therewith. Outward and downward movement of the wall of the cabinet is limited by the arcuate links 5, so that said side wall 10 is converted into a support or shelf to uphold the selected and withdrawn cards or folders B.

From the foregoing it will be understood that the selecting and withdrawing bail 22 15 may be adjusted, readily and accurately, in a position to engage any selected horizontal series of hooks 8 carried by the folders or cards, and that when brought into predetermined position, as indicated by the dial or 20 indicating device on the exterior of the cabinet wall, the bail 22 can be conveniently raised into engagement with the hooks by manipulation of the key or lever 32 and the side of the cabinet dropped to the limit of 25 movement permitted by the links 5 and the guides 6, thereby withdrawing the selected class of folders or cards from the cabinet without disturbing the arrangement of the remaining folders or cards contained therein.

30 I am aware that modifications in the structure within equivalent limits may be made without departing from the spirit and general scope of the invention. I do not limit myself, therefore, to exact details, but

35 What I claim and desire to secure by Letters Patent is:

1. In a filing cabinet arranged to contain 40 folders, the combination with a hinged wall, means for limiting the outward movement of said wall and supporting the same in horizontal position, a selecting device adapted to be adjusted at predetermined vertical positions slidably mounted upon the inner face of said wall, means for maintaining 45 said selecting device in flat adjustment against the inner face of said wall, mechanical connections for adjusting said selecting device, folders contained in said cabinet, engaging members adapted to be adjusted at selected positions on said folders, and means for raising said selecting device to engage selected ones of said engaging members.

50 2. In a filing cabinet arranged to contain folders, the combination with a hinged wall, of engaging members adapted to be adjusted at selected positions on said folders, a bail slidably mounted upon the inner face of said wall, a spring for normally depressing said bail and maintaining it out of engagement with said engaging members, means for raising and lowering said bail to any desired vertical adjustment and means for raising said bail in opposition to said spring for engagement with selected ones of said 55 engaging members.

3. In a filing cabinet arranged to contain 70 folders, the combination of a hinged wall and engaging members adapted to be adjusted at selected positions on said folders; of a selecting device comprising a rock shaft, guides adapted to slide in slots formed in said wall for pivotally supporting said rock shaft; and a bail carried by said shaft; means for raising and lowering said rock shaft comprising slidable sleeves, a movable block operatively connected with said sleeves, and a lever for operating said block; and means accessible from the exterior of said cabinet for raising said rod 75 carried by said shaft whereby said rod may be engaged with selected ones of said engaging members, substantially as specified.

4. In a filing cabinet the combination with a plurality of folders adapted to be arranged 80 therein in predetermined order, a pivoted support constituting a wall of said cabinet, engaging members adapted to be selectively positioned on said folders, means carried by said support operable to engage selected ones 85 of said engaging members, means for preventing the accidental engagement of said means with said engaging members, and a mechanical device for selectively positioning said engaging means, substantially as specified.

5. In a filing cabinet arranged to contain 90 cards and folders, a hinged wall at one side of the cabinet, levers pivoted upon said wall, a rock shaft supported by said levers, an actuating lever for operating said levers 95 effectively to move said rock shaft vertically adjacent to said wall, an engaging device supported by said rock shaft, means for rocking said shaft effectively to move said engaging device into engagement with 100 projections on said cards and folders, and additional means for actuating said rock shaft to disengage said engaging device from the projections on said cards and 105 folders.

6. A filing cabinet comprising a cabinet 110 arranged to contain cards and folders, a pivoted wall closing one side of said cabinet, supports pivoted upon said wall, bearings carried by said supports, a rock shaft or rod 115 journaled in said bearings, a lever for actuating said supports effectively to move said rock shaft vertically, an engaging device supported by said rock shaft, means for rocking said shaft effectively to move said 120 engaging device into engagement with projections on said cards and folders, and an element for disengaging said device from the projections on said cards and folders.

7. A filing cabinet comprising a cabinet 125 arranged to contain cards and folders, a wall having its lower edge pivoted to said cabinet and constituting a closure for one side thereof, means cooperating with said pivot for supporting said wall in a substantially hori- 130

zontal position, a rock shaft or rod supported adjacent to the inner side of said wall, a lever for moving said rock shaft vertically, an engaging device supported by 5 said rock shaft, a lever for rocking said shaft to engage said device with projections on the cards and folders, and automatic means for disengaging said device from said projections when said wall is in its vertical 10 position.

8. A filing cabinet comprising a cabinet arranged to contain cards and folders provided with lateral projections, a wall pivoted at one side of said cabinet and arranged 15 to be moved from a vertical position to a substantially horizontal position, a rock shaft or rod supported horizontally adjacent to the inner side of said wall, a bail supported by said rock shaft and operative to 20 engage said projections on said cards and folders, means holding said shaft or rod in position to support said bail out of engagement with said projections, a lever attached to said rock shaft and operative to rock said 25 shaft to engage said bail with said projections, means for moving said shaft and a bail to position to engage projections in different horizontal planes, and means for preventing accidental movement of said shaft 30 and bail.

9. In a filing cabinet arranged to contain cards and folders provided with lateral projections, a pivoted wall closing one side of said cabinet, an engaging bail supported by 35 said wall, means for moving said bail to various vertical adjustments adjacent to said wall, means for preventing accidental misplacement of said bail, automatic means holding said bail out of engagement with 40 said projections, and manipulative means for engaging said bail with said projections.

10. In a filing cabinet arranged to contain cards and folders provided with lateral projections, a wall closing one side of said cabinet, means for pivotally supporting said 45 wall whereby said wall is enabled to be moved outwardly on its pivot, an engaging bail adjustably supported adjacent to the inner side of said wall, a lever operative to 50 move said bail to various adjustments, means for latching said lever to prevent accidental movement of said bail, a spring holding said bail out of engagement with said projections, a lever manipulative effectively to engage 55 said bail with said projections, and indexes indicating the position of the bail, substantially as specified.

11. In a filing cabinet arranged to contain cards and folders having lateral projections, 60 a hinged wall closing one side of said cabinet, an engaging device supported by said wall for vertical adjustment, manual means for moving said engaging device vertically to position to engage projections on said 65 cards and folders in any selected horizontal

plane, means for preventing accidental movement of said engaging device, and means for operating said engaging device effectively to engage the same with said projections, substantially as specified.

70

12. In a filing cabinet, the combination with cards and folders deposited in the cabinet, and lateral projections on said cards and folders in various horizontal planes, of a hinged wall closing one side of the cabinet 75 adjacent to said projections, an engaging device supported by said wall for vertical adjustment, means for moving said engaging device to any selected horizontal plane 80 in position to engage with said projections in any selected horizontal plane, manipulative means for engaging said device with said projections, and automatic means for disengaging said device from said projections.

85

13. In a filing cabinet, the combination with cards and folders deposited in the cabinet, and lateral projections in connection with said cards and folders in various horizontal planes, of a wall hinged at the side 90 of said cabinet adjacent to said projections, provision upon said wall designating the horizontal planes in which said projections are positioned, an engaging device supported by said wall for vertical adjustment, means for moving said engaging device vertically to any horizontal plane designated by said wall whereby said engaging device will be in position to engage with a selected 100 number of said projections, manipulative means for engaging said engaging device with said projections after said device has been positioned as aforesaid, and means limiting movement of said hinged wall.

95

14. In a filing cabinet, the combination with a plurality of cards and folders deposited in a cabinet, and projections extending from the edges of said cards and folders in various horizontal planes according to predetermined classifications, of a wall hinged 110 at the side of said cabinet adjacent to said projections and being movable outwardly and downwardly, links limiting downward movement of said wall, an engaging device, a rockable support adjustably supporting 115 said engaging device upon said wall, means for moving said support and engaging device to position to engage any selected class of said projections, visible means indicating the class with which said engaging device is positioned to engage, an automatic actuating device normally holding said engaging device disengaged from said projections, and means for moving said engaging device into engagement with said projections.

120

15. In a filing cabinet, the combination with series of cards and folders deposited in the cabinet, and projections extending laterally from said cards and folders, of a device operable to engage with predetermined 130

125

- ones of said projections, an actuator normally holding said device out of engagement with said projections, means for positioning said device to engage any desired ones of 5 said projections, means for preventing accidental movement of said engaging device, a hand lever operable to engage said engaging device with said projections, and an indicator controlled by said engaging device designating what series of hooks said engaging 10 device is positioned to engage.
16. In a filing cabinet, a wall hinged at one side of said cabinet, levers pivoted to said wall, bearings pivoted to said levers, a 15 rockable support journaled in said bearings, a vertically movable member for actuating said levers to move said rockable support vertically, a lever for moving said member vertically, a latching device for preventing 20 accidental movement of said levers, and a bail carried by said rockable support, for the purpose set forth.
17. In a filing cabinet, a wall hinged at one side of said cabinet, a vertically movable 25 support carried by said wall, means for moving said support vertically, a latching device preventing accidental movement of said support, an indicating device indicating the position of said support, an engaging device 30 carried by said support, automatic means for actuating and yieldingly holding said engaging device in substantially the same vertical plane with said support, and means for manipulating said engaging device for 35 the purpose specified.
18. In a filing cabinet, a hinged wall closing one side of said cabinet, a number of levers pivoted upon said hinged wall, a bearing supported by each of said levers, a rock 40 shaft journaled in said bearings, a lever pivoted upon the opposite side of said wall from said first-named levers, devices actuated by said second-named lever for moving said first-named levers effectively to raise and 45 lower said rock shaft, latching means for holding said levers against accidental movement, and an engaging device carried by said rock shaft for the purpose specified.
19. In a filing cabinet, the combination 50 with a wall closing one side of said cabinet, and a support pivotally supporting said wall, of a rock shaft at the one side of said wall, levers pivoted to the inner side of said wall, bearings on said levers in which said 55 rock shaft is journaled, a hand lever pivoted to the outer side of said wall, devices actuated by said hand lever for moving said first-named levers effectively to raise and to lower said rock shaft, an engaging device 60 carried by said rock shaft, automatic means for holding said engaging device yieldingly in substantially the same vertical plane with said rock shaft, and a lever accessible from the outer side of said wall for controlling 65 said engaging device.
20. In a filing cabinet, the combination with a pivotally supported wall, and means limiting movement of said wall, of a number of levers pivoted to the inner side of said wall, bearings supported by said levers, 70 an actuating lever pivoted to the outer side of said wall, means controlled by said actuating lever for actuating said first-named levers effectively to raise and to lower said rock shaft, means preventing accidental movement of said levers and said rock shaft, an engaging device supported by said rock shaft, a lever for controlling said engaging device for the purpose specified, and means on the outer side of said wall indicating the 75 position of said rock shaft and engaging device, substantially as specified.
21. In a filing cabinet, a wall hinged at one side of said cabinet, levers pivoted to said wall, bearings pivoted to said levers, 80 a rockable support journaled in said bearings, a vertically movable member for actuating said levers to move said rockable support vertically, a lever for moving said member vertically, a pin-in-slot connection 85 between said second-named lever and said member, a latching device for preventing accidental movement of said second-named lever, and a bail carried by said rockable support, substantially as described.
22. In a filing cabinet, the combination 90 with cards and folders deposited in the cabinet, and lateral projections on said cards and folders, of a hinged wall closing one side of the cabinet adjacent to said projections, an engaging device supported by said wall, means holding said engaging device out of engagement with said projections, means for moving said engaging device into engagement with said projections, and 95 means connecting said wall with stationary parts of the cabinet for supporting said wall in a substantially horizontal position.
23. In a filing cabinet, a cabinet arranged 100 to contain cards and folders having lateral projections in various horizontal planes, a hinged wall closing one side of said cabinet and movable from a vertical to a horizontal position, links connecting said wall with said cabinet for supporting said wall in a 105 horizontal position, an engaging device supported by said wall for adjustment toward and from the hinge axis, manual means for moving said engaging device to position to engage projections on said cards and folders 110 in any selected horizontal plane when said wall is in vertical position, means for operating said engaging device effectively to engage the same with said projections, and means for preventing accidental movement 115 of said engaging device, substantially as described.
24. In a filing cabinet, a wall hinged at one side of said cabinet and movable from a vertical to a horizontal position, means 120
- 125
- 130

6
for supporting said wall in a horizontal position, a movable member carried by said rock shaft, means for supporting said rock shaft, means controlled by said movable member for moving said rock shaft toward and from the horizontal edges of said wall, a bail carried by said rock shaft for the purpose set forth, and means for actuating said rock shaft to move said bail

to different positions with respect to said shaft, substantially as described.

In witness whereof, I have signed this specification in the presence of two subscribing witnesses.

HARRY A. WARDY.
